UNITED STATES PATENT OFFICE.

JOHN J. DUKET, OF TOLEDO, OHIO.

CONTAINER-OPENING TOOL.

Application filed April 4, 1921. Serial No. 458,433.

To all whom it may concern:

Be it known that I, JOHN J. DUKET, a citizen of the United States of America, residing at Toledo, Lucas County, Ohio, have invented new and useful Container-Opening Tools, of which the following is a specification.

This invention relates to receptacle opening tools.

10 This invention has utility when incorporated in a lever or handle having a blade and an engaging lip.

Referring to the drawings:—

15 Fig. 1 shows a display card illustrating the device in use together with the manner of mounting the devices for display on said card, parts being broken away;

Fig. 2 is a side elevation of the tool of Fig. 1;

20 Fig. 3 is a longitudinal section of the tool of Fig. 1 showing the tool in position for removing a seal or cap from a bottle, as distinguished from the perspective portion of Fig. 1 showing the tool for opening a can;

25 Fig. 4 is a detail perspective view of a fulcrum for the tool of Fig. 2;

Fig. 5 is a fragmentary detail view of this tool with a convex fulcrum;

30 Fig. 6 is a fragmentary view of this tool equipped with a concave fulcrum; and

Fig. 7 is a fragmentary view of this tool equipped with a cylindrical fulcrum.

A display card 1 is shown as having a strap 2 with openings 3, 4, adjacent thereto, 35 as a carrier for the tools of this invention which are shown as comprising a pair of side ribs 5 connected by a loop portion 6. Intermediate these side portions 5 and connecting said side portions or ribs is a webbing 7 terminating in a lip 8 short of or adjacent the loop 6, thus leaving an opening into which may partially be inserted a bottle 9 having a seal 10 under which the lip 8 may engage with the loop 6 against the top thereof so 40 that prying action occurs. With the loop 6 as the fulcrum, the lip 8 as the work, and the handle 5, 7, as the power, there may be a lever simply effective for removing the cap as crimped or otherwise held in position 45 upon the container or receptacle 9.

Remote from this lip 8 the handle has offset portion 11 as a second lip provided with a seat 12 therein. Projection 13 between the ribs 5 and rising from the web 7 is in the region of the seat 14 for a blade 15 which may be anchored by screw 16 to form an exten-

sion for the handle or lever 5, 6, 7. A flat piece of hardened steel 17 inserted into the seat 12 of the offset lip 11 is by the single screw 16 anchored in operative position as a 60 fulcrum when this blade 15 is assembled with the handle. This blade 15 may have its pointed terminus forced through a sheet-metal top 17' of a can 18 in such proximity to the side of this can that the blade 15 as 65 directed by the offset lip 11 will ride close to the edge of the can.

With this double-edged blade 15 as the work, and the hardened member 17 as the fulcrum, the power may be applied to the 70

handle 5, 6, 7, in seesawing progress for closely trimming the lid 17' away from the edge of the can 18, thereby simply and neatly giving a full opening for the can allowing

75 neat and convenient removal of even one-piece contents therefrom. The rocking of the handle 5, 6, 7, may be directed away from the plane of the side of the can 18 for drawing the blade into position directly against the side of the can 18. The com-

pleted article at this offset lip 11 which 80

serves to conveniently direct the blade as to the can has a further function in providing a simple display mounting support for the

article by inserting the lip 11 through opening 4 under strap 2 to position at opening 3 85

with the blade 15 over this strap 2. The webbing section 7 is shown as defined from the lip 8 and the seat 14 so that in practice 90

this portion 7 may be a substitute part in the manufacture for advertising or identification data cast therein.

The feature of the fulcrum and its can 95 edge coaction while effectively taken care of by the fulcrum 17 may in some instances be

advantageously handled by departing from the contour of the fulcrum 17. In Fig. 5

there is shown a convex fulcrum 20 which would tend to direct the can edge either to- 100

ward or away from the blade as the handle may be manipulated. For varying the re- 105

sistance to such shifting there may be pro- vided a concave fulcrum 21 of Fig. 6. Simi- 110

lar action to that of the fulcrum 20 may be experienced by cylindrical fulcrum 22 of Fig. 7. In Fig. 7 there is also shown instead of the guide stud or projection 13 at the seat 14 a screw 23 which, with the screw 16, completes the holding of the blade 15 as to the handle.

There is accordingly as herein disclosed a lever tool with container engaging lips for

coaction in lever operation in permitting access to bottle or can containers.

The fragmentary tool shown at the left on the card in Fig. 1 embodies a blade 24 sharpened on one side only. This tool is such that it may be satisfactorily operated even without a fulcrum and without the tilting to bring it into proximity with the side of the can in cutting.

10. What is claimed and it is desired to secure by United States Letters Patent is:—

1. A tool handle embodying a loop and ribs extending therefrom provided with a web filler therebetween extending to provide

15 a pair of seats, a fulcrum in one of said seats, and a blade mounted in the other seat to hold the fulcrum in its seat.

2. A tool handle embodying a loop and ribs extending therefrom provided with a web filler therebetween to provide a fulcrum seat, a fulcrum in said seat, and extension means from the filler forming a blade.

3. A tool handle embodying a loop and ribs extending therefrom provided with a web filler therebetween and extension means

from the filler forming a blade remote from the loop, said handle being offset to provide a symmetrically pointed guide lip laterally spaced from the blade, said offset providing a seat, between the ribs and a removable 30 fulcrum in the seat.

4. A tool handle having an extension lip, said handle provided with seats, one of which is in the lip, and one in the handle portion, a fulcrum mounted in the lip seat, 35 and a blade mounted in the handle seat and extending therefrom over the fulcrum to anchor the fulcrum in position.

5. A tool handle embodying a loop, ribs extending therefrom, and a web between the 40 ribs terminating in one direction in an offset to provide a lip, the offset lip being provided with a seat, a fulcrum in the offset seat, a blade engaging the handle web between the ribs and extending along the offset lip to engage the fulcrum, and a screw 45 for anchoring the blade to the handle and thereby mounting the fulcrum in position.

In witness whereof I affix my signature.
JOHN J. DUKET.
